[57] CLAIM

The ornamental design for a tire lift and lug remover set, as shown.

DESCRIPTION

FIG. 1 is a perspective view of a tire lift and lug remover set showing our new design;

FIG. 2 is a top plan view of a first portion thereof;

FIG. 3 is a bottom plan view thereof;

FIG. 4 is a right side elevational view thereof;

FIG. 5 is a left side elevational view thereof;

FIG. 6 is front elevational view thereof;

FIG. 7 is a rear elevational view thereof;

FIG. 8 is a top plan view of a second portion thereof;

FIG. 9 is a bottom plan view thereof;

FIG. 10 is a left side elevational view thereof;

FIG. 11 is a right side elevational view thereof;

FIG. 12 is a rear elevational view thereof;

FIG. 13 is a front elevational view thereof;

FIG. 14 is a top rear perspective view of the tire lift and lug remover set in its folded position; and,

FIG. 15 is a bottom front perspective view thereof in its folded position.
The portions of the set have been shown separately in FIGS. 1-13 for clarity of illustration.
